UNITED STATES PATENT OFFICE.

ALEXANDER NYMAN, OF WILKINSBURG, PENNSYLVANIA, ASSIGNOR TO WESTINGHOUSE ELECTRIC & MANUFACTURING COMPANY, A CORPORATION OF PENNSYLVANIA.

LOUD-SPEAKING DEVICE.

Application filed September 16, 1922. Serial No. 588,548.

To all whom it may concern:

Be it known that I, ALEXANDER NYMAN, a citizen of the United States, and a resident of Wilkinsburg, in the county of Allegheny and State of Pennsylvania, have invented a new and useful Improvement in Loud-Speaking Devices, of which the following is a specification.

My invention relates to sound-reproducing apparatus, having particular relation to telephone transmitters or receivers.

One object of my invention is to provide a new embodiment of a loud speaking device, wherein signal currents are faithfully translated into sound waves, or vice versa, without distortion.

Another object of my invention is to provide sound reproducing apparatus, wherein the vibratory elements are caused to move in a substantially rectilinear direction only, thereby eliminating many of the well known undesirable effects characteristic of the prior art telephone apparatus employing rigidly mounted vibratory elements.

Still another object of my invention is to provide apparatus of the class described above, which is characterized by its extreme simplicity of arrangement and accessibility of parts requiring adjustment and which lends itself to inexpensive quantity production methods of manufacture, the several parts of which may be easily made in existing automatic machinery and may be readily assembled with a minimum expenditure of time and of money.

According to my invention, I provide a telephone transmitter or receiver, wherein a pair of vibratory armature elements are employed which constitute the pole terminals of a permanent magnet. The vibratory elements are movable bodily in a substantially rectilinear direction between oppositely directed pairs of pole pieces, which are energized by a magnetizing winding carrying signal currents. The vibration of the armature member incident to the excitation of the magnetizing winding may be transmitted to a diaphragm member to produce sound waves, all as described more fully hereinafter.

With these and other objects and applications in view, my invention further consists in the nature, the mode of operation and the constructional details hereinafter

described and claimed and illustrated in the accompanying drawing, wherein:

Figure 1 is a top plan view of one form of sound-reproducing apparatus embodying my invention;

Fig. 2 is a vertical longitudinal sectional view of the apparatus shown in Fig. 1, taken on the line II-II thereof;

Fig. 3 is a similar view taken on the line III-III of Fig. 1.

Fig. 4 is a detail view of a metal blank or punching from which the yoke member may be formed.

In one embodiment of my invention, a permanent magnet 1 is provided having opposite end portions 2 and 3 facing one another in spaced relation. A vibratory armature construction 4 designed to be movable bodily in a substantially rectilinear direction is positioned in the space intermediate the end portions or poles 2 and 3 and is carried at its opposite ends by means of magnetizable spring members 5 and 6. The latter members 5 and 6 are respectively secured to the vertically extending portions 7 and 8 of L-shaped steel frames 9 and 11, the horizontally extending portions 12 and 13 of which are secured respectively, to the top sides of the end portions 2 and 3 of the magnet 1, as shown in the drawing.

The armature construction 4 comprises a pair of horizontally positioned magnetizable members 14 and 15 of rectilinear shape, the adjacent sides of which are mechanically connected by means of a member 16 of non-magnetizable material, for reasons which will be apparent hereinafter. The opposite sides of the armature members 14 and 15 are flexibly secured to the vertical portions 7 and 8 of the steel frames 9 and 11 by means of the spring connections 5 and 6, respectively, as just stated. The magnetic circuit of the permanent magnet 1 is thus extended by means of the paths provided through the several steel frames 9 and 11 and the flexible connecting means 5 and 6 to the armature members 14 and 15, respectively, thereby permitting the armature members 14 and 15 to serve as pole terminals for the permanent magnet 1.

The vibratably mounted armature members 14 and 15 may be caused to vibrate by means of an electromagnet structure 17 which is supported in the space intermedi-

ate the ends 2 and 3 of the permanent magnet 1 by means of a frame 18 of non-magnetizable material, such as brass, which is rigidly secured to the vertical portions 7 and 8 of the steel frames 9 and 11, all as explained more fully hereinafter. A non-magnetizable material for the frame 18 is herein specified to prevent the frame 18 from operating to short circuit the air-gap 10 path between the ends of the permanent magnet 1.

The electromagnet structure 17 just mentioned, comprises a yoke member 19 which is provided with a magnetizing coil 20 carrying variable currents of signal frequency. The yoke member 19 may be originally constructed from a punching or blank 21 of magnetizable material, as shown in Fig. 4, and comprises a central core portion 22 upon 20 which the exciting coil 20 is mounted. The opposite ends of the central core portion 22 are extended to form the portions 23 and 24 which terminate, respectively, in pairs of polar projections 25, 26, and 27, 28.

25 In the construction of the yoke member 19 from the blank 21, the end portions 23 and 24 are bent along the lines 23a and 24a, respectively, into upright position. The legs or polar extensions 25 and 27 are then 30 bent inwardly along the lines 29 and 31, respectively, to cause a portion of the projection 25 to be disposed immediately above a corresponding portion of the projection 27, the space 32 therebetween being determined by the relative positions of the lines 35 29 and 31. The remaining projections 26 and 28 are similarly bent along the lines 33 and 34, respectively, to cause a portion of the projection 28 to be disposed immediately 40 over a portion of the projection 26, thereby forming an air gap 35 which is positioned in alignment with the air gap 32. The construction of the yoke member 19 may, of course, be variously modified within 45 the scope of my invention as by employing a separate core for the magnetizing coil 20 which is rigidly secured to the end portions 23 and 24.

When the magnetizing coil 20 is excited 50 by electrical energy, a pair of magnetic circuits, as indicated by the dotted arrows a_1 and a_2 , are established having the air gaps 32 and 35, respectively, therein, the magnetic flux traversing the air gaps being in 55 opposite directions. The pairs of horizontal projections 25, 27 and 28, 26 thus constitute pairs of oppositely directed, pole pieces for the electromagnet structure 17.

In the complete assembly of my invention 60 shown in Figs. 1, 2 and 3, the electromagnetic structure 17, as previously stated, is supported by the brass ring 18 which is secured to the vertically upright portions 23 and 24 of the yoke member 21, the magnetizable armature members 14 and 15 being

disposed in the air gaps 32 and 35. The exact position of the armature members 14 and 15 in the air gaps 32 and 35, respectively, is such as to cause the several armature members to be acted upon by balanced forces, as 70 will be explained more fully hereinafter.

The magnetic circuit of the permanent magnet 1 between the armature members 14 and 15 now comprises a pair of parallel connected paths, as indicated by the solid line 75 arrows in the drawing. The one magnetic circuit extends from the armature member 14 through a portion of the air gap 32, the pole piece 27, the upright portion 24, the pole piece 28 and a portion of the air gap 35 80 to the armature member 15. The other magnetic circuit extends from the armature member 14 through a portion of the air gap 32, the pole piece 25, the base portion 23, the pole piece 26 and a portion of the air 85 gap 35 to the armature member 15.

When the magnetizing winding 19 is not energized, and when the armature members 14 and 15 are disposed in a substantially central position between their corresponding pairs of pole pieces, said armature members are acted upon by opposite magnetic forces of substantially equal intensity. Hence the armature structure 4 is in a balanced condition. 90

When the magnetizing winding 19 is energized, a relative strong magnetic flux is caused to traverse the air gaps 32 and 35 between the several pairs of poles, as previously discussed. When the flux established by the magnetizing winding 19 is in 100 a direction indicated by the dotted line arrows a_1 and a_2 , it is seen that the magnetic forces between the poles 25 and 28 and the armature members 14 and 15, respectively, 105 are increased, whereas the magnetic forces between the poles 27 and 26 and the armature members 14 and 15, respectively, are diminished. The result is a rectilinear motion of the armature toward the poles 25 and 28, which is resisted by the force of 110 the springs 5 and 6.

However, when the direction of the currents through the magnetizing winding 20 is reversed, the magnetic forces of the lower poles 27 and 26 upon the armature members 14 and 15, respectively, are increased in the same proportion that the magnetic forces of the upper poles 25 and 28 upon the said armature members are decreased. Hence, 115 there is a rectilinear motion of the armature members 14 and 15 in the opposite direction towards the lower poles 27 and 26, which motion is again resisted by the force of the springs 5 and 6.

In view of the foregoing, it is apparent 120 that when the magnetizing winding 20 is supplied with vibratory energy, the armatures are vibrated in accordance with the frequency and the intensity of such energy. 125 130

The vibratory motion of the armatures may be transferred to a diaphragm 36, illustrated as having a conical shape, by means of a connector 37 to cause the translation of the vibratory armature energy into sound waves. The periphery of the diaphragm 36 may be positioned between resilient washers 38 and 39, which, in turn, are carried by a non-magnetizable frame 41 secured to the 10 horizontal portions 12 and 13 of the steel frames 9 and 11, respectively, by means of screws 42. The washers 38 and 39 may be held in position by means of an annular member 43 adjustably secured to the supporting member 41 by a thread connection. In operation, the washers 38 and 39 serve merely as a resilient support for the diaphragm 36 and do not appreciably restrict the motion of the periphery thereof, thereby 20 allowing the diaphragm 36 to vibrate freely as a whole.

In order to simplify the description of my invention and to facilitate a clear understanding of the same, I have eliminated 25 from the description and drawings such portions of the complete structure as, for instance, the enclosing casing, which would be readily understood by those skilled in the art.

30 While I have described a preferred embodiment of my invention for the purpose of illustrating its principles of operation and constructional arrangement, it is apparent that certain changes and modifications may be made in the nature, the mode of operation and details of construction without departing from the spirit of my invention. I desire, therefore, that only such limitations shall be imposed thereon as are 35 indicated in the appended claims or demanded by the prior art.

I claim as my invention:

1. In combination, a yoke member providing paths for a pair of interconnected 45 magnetic circuits having air gaps, one individual to each circuit, means for establishing a magnetic flux in said magnetic circuits, said air gaps being so arranged that the magnetic flux traversing one air 50 gap is in opposite direction to that traversing the other, and a permanent magnet having pole pieces of opposite polarities vibratably positioned in said air gaps, respectively.

55 2. In combination, a yoke member providing paths for a pair of parallel magnetic circuits having air gaps, one individual to each circuit, means for establishing a varying magnetic flux in said magnetic circuits, the magnetic flux traversing one air gap being in an opposite direction to that traversing the other, and a permanent magnet having pole pieces of opposite sign vibratably positioned in said air gaps, respectively, the 60 magnetic flux emanating from one pole piece

traversing said magnetic circuits to the other pole piece.

3. In combination, a yoke member providing paths for a pair of parallel magnetic circuits having an air gap individual to each circuit, means for establishing a varying magnetic flux in said magnetic circuits, said air gaps being so arranged that the magnetic flux traversing each is in opposite directions, a permanent magnet, magnetizable armature members constituting pole pieces for said permanent magnet vibratably positioned in said air gaps and non-magnetic means for mechanically connecting 70 said armature members. 75

4. In combination, a permanent magnet, a pair of vibratably positioned armature members constituting opposite poles for said permanent magnet, a pair of pole pieces disposed upon opposite sides of each armature member in such manner as to provide air gaps therebetween, and a yoke member associating said pole pieces in such relation that the pole pieces of one pair are disposed in opposite relation to the pole pieces of the other pair. 80

5. In combination, a permanent magnet, a pair of mechanically connected vibratably positioned armature members constituting opposite poles for said permanent magnet, a pair of pole pieces for each armature member and disposed, respectively, upon opposite sides thereof in such manner as to provide air gaps therebetween, a yoke member, and a winding thereon, said yoke member associating said pole pieces in such relation that the pole pieces of one pair are oppositely disposed with respect to the pole pieces of the other pair. 90 95

6. In combination, a permanent magnet, a pair of vibratably positioned armature members constituting opposite poles for said permanent magnet, and a yoke member carrying an exciting coil and having divided polar projections forming pairs of pole 100 pieces of opposite sign, one pair of pole pieces being provided for each armature member and disposed upon opposite sides thereof, the pole pieces of one pair being oppositely disposed with respect to the pole pieces of another pair. 105 110 115

7. In combination, a permanent magnet, a pair of vibratably positioned armature members constituting opposite poles for said permanent magnet, means for causing said members to vibrate in unison, and a yoke member comprising a central portion carrying an exciting coil and end portions having divided polar projections, one pair of poles being associated with each armature member and disposed adjacent to opposite sides thereof, the poles of one pair being oppositely disposed with respect to the poles of another pair. 120 125

8. In combination, a yoke member pro-

vided with a central core portion and having divided polar projections extending from opposite ends of said central portion, the ends of the projections from opposite 5 ends being disposed one above the other to form pairs of spaced poles of opposite polarity, said pairs of poles being oppositely arranged, a permanent magnet, an armature member vibratably positioned in the 10 space intermediate each pair of poles in balanced relation thereto, said armature members constituting pole pieces for said permanent magnet, and an exciting coil encircling said core portion and carrying currents tending to unbalance the balanced 15 relation of said armature members.

9. In combination, a yoke member provided with a central core portion and having divided polar projections extending 20 from opposite ends thereof, the ends of the projections from opposite ends of said core being disposed one above the other to form pairs of spaced poles of opposite polarity, said pairs of poles being oppositely arranged, a permanent magnet, armature 25 members vibratably positioned in the space intermediate said pairs of poles in balanced relative relation thereto, non-magnetic means mechanically connecting said armature members to cause the same to vibrate as a unit, an exciting coil carrying vibratory 30 electrical currents for disturbing said balanced relation, a diaphragm and means for transferring the vibratory motion of the 35 armature members to the diaphragm.

10. In combination, a yoke member provided with a central core portion and with divided polar projections extending from opposite ends thereof, the ends of the pro-

jections from opposite ends of said core being disposed one above the other to form pairs of spaced poles of opposite polarity, said pairs of poles being oppositely arranged, a permanent magnet, armature members having corresponding portions disposed in the space intermediate said poles and movable bodily in a substantially rectilinear direction toward and away from the respective poles and having other portions secured to the ends of the permanent magnet, non-magnetic means mechanically connecting said armature members to cause the same to vibrate in unison, and an exciting coil encircling said central core portion. 40 45 50 55

11. In combination, a yoke member provided with a central core portion having a pair of divided polar projections extending from opposite ends thereof, the ends of said projections from opposite ends of said core portion being disposed one above the other to form pairs of spaced poles of opposite polarity, said pairs of poles being oppositely arranged, a permanent magnet, vibratory magnetizable members disposed in the space intermediate said poles and movable bodily 60 65 70 75 therein in a substantially rectilinear direction, non-magnetic means mechanically connecting said armature members to cause the same to vibrate as a unit, flexible magnetizable means for securing said armature members to adjacent ends of said permanent magnet, and a coil encircling said core portion carrying vibratory electrical currents.

In testimony whereof, I have hereunto subscribed my name this 30th day of August, 1922.

ALEXANDER NYMAN.
